UNITED STATES PATENT OFFICE.

ALPHONZO LLOYD, OF WASHINGTON, PENNSYLVANIA, ASSIGNOR TO THE R. T. FRENCH COMPANY, OF ROCHESTER, NEW YORK, A CORPORATION OF NEW YORK.

DESIGN FOR A BOTTLE OR JAR.

47,002.

Specification for Design.

Patented Feb. 23, 1915.

Application filed November 27, 1914. Serial No. 874,341. Term of patent 14 years.

To all whom it may concern:

Be it known that I, ALPHONZO LLOYD, a citizen of the United States, residing at Washington, in the county of Washington and State of Pennsylvania, have invented a new, original, and ornamental Design for Bottles or Jars, of which the following is a specification, reference being had to the accompanying drawing, forming part thereof.

The figure is an elevation of a bottle or jar, showing my new design.

I claim:

The ornamental design for a bottle or jar, as shown.

ALPHONZO LLOYD.
